HARRY HURASON, OF BROOKLYN, NEW YORK

LOCKING JOINT

Application filed September 19, 1924. Serial No. 738,576.

This invention relates to adjustable mechanical couplings and more particularly to joints of the type adapted to lock two elements in any of various angular relations. In one of the numerous possible applications, the invention serves as a universal connection between an implement such as a brush or broom and the operating handle thereof to permit readily setting the handle in any desired angular relation to the brush so that convenient operation under varying conditions of use is assured. An object of the invention is to provide an inexpensive reliable locking joint of this character which may be effectively locked in any desired position of adjustment and which may be expeditiously and easily shifted and relocked to change the adjustment.

The joint comprises a member adjustable about an axis normal to the brush head to determine the vertical plane of the handle, the inclination of which is determined by rotary adjustment about a horizontal axis carried by the member.

Preferably the two axes of adjustment are substantially in a plane disposed at right angles to the brush head or in other words, a plane which is normal to the surface to be operated on by the brush. By virtue of the above arrangement of the centers of adjustment, pressure on the handle will always be translated into substantially direct pressure urging the brush against the surface to be operated upon regardless of the angular relationship between the brush and handle.

In the accompanying drawings:

Figure 1 is a view in side elevation of my improved locking joint, showing the same in use as a coupling member for a brush and brush handle.

Figure 2 is a similar view taken at right angles to Figure 1.

Figure 3 is a longitudinal sectional view on the line 3-3 of Figure 2.

Figure 4 is a similar view on the staggered line 4-4 of Figure 1.

Figure 5 is a view in transverse section on the line 5-5 of Figure 2.

I have designated the three main parts of the lock joint by the reference characters 10,

10a and 10b respectively. The member 10 is adapted to be secured to the head 11 of a brush 12. Member 10a is adapted to be mounted upon the handle 13 of the brush and the member 10b serves as a coupling member for connecting members 10 and 10a and permitting relative universal adjustment thereof.

The particular shape of the member 10 depends entirely upon the character of the brush to which it is to be secured. With a brush having an arched or convex back as shown, the member 10 is a substantially arcuate plate conforming to the curved shape of the brush back and formed at its intermediate portion with a circular boss 15 presenting a flat surface parallel to the surface to be operated upon by the brush. A central opening 16 through the boss permits the insertion of a screw or other appropriate securing device 17 for rigidly connecting the member 10 to the back of the brush.

Member 10a is of general cylindrical shape throughout the major portion of its length presenting a split socket 18 into which the end of the handle is jammed or wedged. Of course, this socket might be formed in other ways to facilitate its firm engagement with the brush handle but I find the particular type illustrated effective and desirable because of its simplicity. An approximately circular extension 19 integral with the closed end of the cylindrical socket member is formed on one face with a series of radially disposed locking teeth 20 adapted to mate with similar teeth 21 on the circular extremity 22 of an upstanding arm 23 forming an integral part of the member 10b. The terminal portion of the arm and the extension of the socket are provided with registering central openings 24 receiving a stud or screw 25 upon which a wing nut 26 works. The nut and screw serving to normally maintain the two sets of radially disposed teeth in interlocked relationship. This screw serves as a pivot about which the handle may be adjusted relative to the member 10a and this pivotal point is in direct vertical alignment

with a central opening 27 in the circular plate 28 from which the arm rises.

The plate and the arm constitute the coupling member 10b, the plate being secured flatly against the flat surface of the boss and the central opening 27 in the plate registering with the opening 16 in the boss so that the screw 17 which is utilized for securing the member 10 to the brush head may also serve as a pivotal or rotary connection between the members 10 and 10b. The plate is formed with an arcuate slot 29 and a binding screw 30 extending through the slot works in a threaded socket 31 in the boss and carries a head 32 for clamping a washer 33 against the upper surface of the plate and preventing relative rotation of the plate and boss. It is thus possible by loosening the binding screw to orientate the brush head to any desired angle relative to coupling member 10b and then to lock the coupling member and the member 10 in adjusted position by tightening the screw.

For adjusting the angular relationship between the handle and the coupling member it is simply necessary to loosen the wing nut 26 rotate the handle on the screw 25 and then tighten the nut to force the toothed faces of the extension 19 and the terminal 22 of the arm 23 into interlocking mating relationship. For facilitating this last mentioned pivotal adjustment of the handle, I prefer to form the mating radially toothed faces of the interlocking members with oppositely disposed sockets 34 and to encircle the intermediate portion of the screw with a coiled expansion spring 35 having its ends bearing in the sockets. Thus when the spring nut 26 is loosened, the spring 35 automatically separates the toothed members 19, 22 and moves them to a position where they may be relatively rotated about the screw.

It will be noted that the arm is angularly disposed to the plate in order to bring its toothed terminal portion approximately over the center of the plate. Thus the two centers of adjustment namely the center of pivotal adjustment of the member 10a and the coupling and the center of rotary adjustment of the member 10 and the coupling are in direct alignment and in a plane disposed at right angles to the surface upon which the brush is adapted to act. By virtue of this construction when the parts are locked in any desired angular relationship and force or pressure on the handle tending to urge the brush against the surface to be operated upon will always be translated to said surface in terms of a substantially direct thrust. In other words, there is no substantial tendency for the brush to tilt or turn in operation regardless of its position relative to the operating handle.

When the invention is used with a brush having a convex back as shown the arcuate plate effectively serves to prevent relative rotation of the brush and the member 10a.

When the member 10a, however, is used with a flat backed brush it is obvious that some means supplemental to the screw should be provided for preventing rotation in use. I find that this may be effectively accomplished by using a slightly longer clamping screw which will bite into the back of the brush and the screws will cooperatively prevent rotation.

It will, of course, be understood that my universal joint clamp is applicable for the connection of the handle of any implement, such as a cutting tool, painting brush mop and the like. Moreover, the invention is not confined in its application to implements, but may obviously be applied for the angular adjustment of any device mounted on a pedestal, bracket or other support. For instance, the invention is applicable as the joint between an electric fan and its supporting bracket, pedestal or other support, also to adjustable display racks and in numerous other relations in which two elements are to be readily set and maintained in adjusted position. The manufacture and assembly of the parts is simple and direct and can be affected by unskilled labor.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting case.

I claim:

1. A device of the class described including an arcuate plate attachable to the back of a brush and formed with a flat faced circular boss, a socket member attachable to a brush handle, a coupling member rotatably connected to the boss and pivotally connected to the socket member said coupling member including a circular plate a headed screw passed through aligned openings in the center of the boss and plate holding them together and holding the arcuate plate to the brush, the screw being unthreaded where it passes through the circular plate to permit rotation of the latter over the surface of the boss about the screw as a center means to clamp the circular plate and the boss together in any desired position of relative adjustment to lock them against relative movement, an angular arm integral with the edge of the plate and extending inwardly over the center thereof, a radially toothed surface at the extremity of the arm, said

socket member including a radially toothed extension mating and adjustably interlocked with said first mentioned radially toothed surface the prolonged axis of the coupling member bisecting the axes of the toothed members perpendicularly.

2. The combination with a brush having a convex back of an arcuate plate conforming to the shape of the back and secured thereto, a flat topped circular boss integral with the plate, a second plate rotatably mounted centrally of the boss and having an arcuate slot therein, the means to secure the first mentioned plate to the brush to hold the two plates together and to serve as a rotary center for the circular plate comprising a headed screw passed through aligner openings in the plates and including an unthreaded portion at the region of the circular plate, a clamping screw working through the slot and boss for locking the slotted plate against rotation relative to the boss, an angularly disposed arm rising from the edge of the slotted plate and extending inwardly over the center thereof, said arm terminating in a circular extension presenting a radially toothed surface approximately perpendicular to the slotted plate, a socket member receiving a brush handle, an extension on the slotted plate similar to the terminal end of the arm and presenting a radially toothed face mating with the toothed face of the extension, a bolt passed through the two toothed members and means for effecting relative movement thereof along the bolt to move the toothed faces into locking engagement, with the brush handle disposed in any desired angular relationship relative to the brush the prolonged axis of the coupling member bisecting the axes of the toothed members perpendicularly.

Signed at New York, in the county of New York and State of New York this 12th day of September, A. D. 1924.

HARRY HURASON.
